Primary Examiner — Natasha Vujcic(74) *Attorney, Agent, or Firm* — Sanchelima & Associates, P.A.; Jesus Sanchelima; Christian Sanchelima(57) **CLAIM**

The ornamental design for a portable cooling station as shown and described.

DESCRIPTION

FIG. 1 is an isometric view of a portable cooling station showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design. The broken lines in the figures show portions of the portable cooling station that form no part of the claimed design.
